TRUNNION TILT CORRECTOR APPARATUS

William B. Jordan and Frithiof V. Johnson,
Schenectady, N. Y., assignors to General Electric Company, a corporation of New York

Application April 14, 1938, Serial No. 201,949

10 Claims. (Cl. 235—61.5)

This invention relates to the control of guns and the like, more particularly to the control of guns on swaying foundations, such as on a rolling ship, and it has for its object the provision of improved apparatus for directing guns whereby corrections are applied to the guns compensating for the inclination of the trunnions of the guns due to the roll of the ship, or other foundation on which the guns are mounted.

In the directing of guns, the calculated adjustments of range to be applied to the gun in elevation and of deflection to be applied to the gun in train are based on the assumption that the adjustments will be applied to the gun in true vertical and horizontal planes; that is, it is assumed that the trunnions of the gun about which the gun is elevated lie in a true horizontal plane, and that they are mounted so that the gun is adjusted in train on a true vertical axis. The gun, however, is usually mounted with its trunnions parallel with the deck of the ship on which the gun is carried, and thus, it is adjustable in elevation on an axis which is parallel to the deck and in train in an axis which is perpendicular to the deck. Therefore, it is only when the ship is on even keel that the gun is adjusted on train and elevation axes which are truly vertical and horizontal. Consequently, it is only when the ship is on even keel that the calculated corrections for train and deflection are properly applied to the gun.

This invention contemplates the provision of improved apparatus whereby the roll or inclination of the ship or other support on which the gun is mounted about the line of sight of a target is continuously introduced as a correction so that the calculated elevation and train adjustments, based on the assumption that the gun is to be adjusted in true vertical and horizontal planes, are continuously modified in accordance with the inclination of the ship so as to direct the adjustment of the gun to cause it to assume continuously the position in space that it would occupy when adjusted with reference to the true vertical and horizontal. It is to be understood that when the deck of the ship is horizontal, the line of sight will be a horizontal line from the deck to the target. As the ship rolls and pitches, there is an inclination or rolling of the deck about this horizontal line as an axis. It is this roll or inclination of the deck which the apparatus of this invention is intended to compensate for.

In accordance with this invention, suitable apparatus is provided comprising means for utilizing the calculated values of elevation and deflection corrections, and also utilizing continuously the angle of cross roll of the ship about the line of sight so as to modify the calculated values of elevation and deflection and regenerate them continuously as corrections which can be applied

directly to the gun in elevation and train to cause it to assume the proper position in space with reference to the true vertical and horizontal.

For a more complete understanding of this invention, reference should be had to the accompanying drawing in which Fig. 1 is a diagrammatic representation of trunnion tilt corrector apparatus arranged in accordance with this invention; and Fig. 2 is a diagrammatic representation illustrating the trunnion tilt problem which is solved by the apparatus of Fig. 1.

Referring to the drawing, this invention has been shown in one form as applied to apparatus intended to correct for the trunnion tilt of a gun mounted on shipboard.

It will be understood that in directing a gun on a target, the range correction, which will be called "elevation correction" hereinafter, is a function of the range of the target, velocity and direction 20 of the wind, speeds and directions of ship and target, etc., as calculated, and is an angular adjustment to be applied to the gun in a vertical plane. The train correction, which will be called "deflection correction," is calculated from the 25 velocity and direction of the wind, drift, speed, direction of ship and target, etc., as calculated, and is an angular adjustment to be applied to the gun in a horizontal plane. As pointed out previously, the gun mounted on shipboard is adjusted in elevation on its trunnions in a plane 30 which is perpendicular to the deck and in a train plane which is at right angles to the elevation plane. It is clear, therefore, that when the ship is rolling so that the gun support inclines from 35 the horizontal, the gun is not rotated in true vertical and horizontal planes respectively, but in planes at angles to these planes, the magnitude of the angles depending on the inclination of the ship.

It is a function of the apparatus of this invention to utilize the calculated adjustments in elevation and deflection to be applied to the gun, and modify them continuously in accordance with the angle of cross roll of the ship about the line 45 of sight to the target; and to regenerate the values in elevation and deflection that must be applied to the gun to cause it to be directed in the proper direction. It is to be understood that it is assumed in this application that when the ship is 50 on even keel its deck will be truly horizontal. In practice, it may be that the deck is not in a true horizontal plane when the ship is on even keel; in such cases, a reference plane must be established. It is intended for the sake of simplicity 55 to use the term "deck" to denote the reference plane whether it be the actual ship's deck or the established plane.

Referring to Fig. 2, there is illustrated a sphere that illustrates diagrammatically the trunnion tilt problem which is solved by the apparatus of

Fig. 1. Let it be assumed that the point P on the surface of a sphere is representative of the direction in which the gun should be directed. This point P has an elevation value E and a deflection value D referred to axes *a* and *b* representative of the true horizontal and true vertical respectively. It will be understood that the values E and D are the calculated adjustments to be applied to the gun in elevation and train, respectively. Now let it be assumed that the axes *a* and *b* are rotated through the angle γ to the positions *a'* and *b'*. This is the condition when the deck of the ship rolls about the line of sight to a target through the angle γ , known as the angle of cross roll. The angle γ is the angle from the horizontal that the deck tilts around the line of sight, which line of sight, as pointed out previously, is the horizontal line between the sight and the target when the deck is at even keel. It will be apparent that when the axes are so rotated through the angle γ if the point P is to retain the same position in space that it had before, the coordinates E and D respectively become the coordinates E_c and D_c respectively. It is the values of the corrected coordinates E_c and D_c that are desired. The exact formulae for the solution of this problem are the trigonometric equations:

$$(1) \ Sin E_c = \Sin E \ Cos \gamma - \Cos E \ Sin \gamma \ Sin D$$

$$(2) \ Tan D_c = \frac{\Sin E \ Sin \gamma + \Cos E \ Cos \gamma \ Sin D}{\Cos E \ Cos D}$$

Equations 1 and 2 are derived as follows: Referring to Fig. 2, from well-known spherical trigonometrical formula applied to the spherical triangle pMN,

$$\Cos pN = \Cos pM \ Cos MN + \Sin pM \ Sin MN \ Cos \text{angle } pMN$$

and since

$$\begin{aligned} pN &= 90^\circ - E_c \\ pM &= 90^\circ - E \\ MN &= \gamma, \end{aligned}$$

and

$$\text{Angle } pMN = 90^\circ + D$$

the above equation may be written as follows:

$$\Cos(90^\circ - E_c) = \Cos(90^\circ - E) \ Cos \gamma + \Sin(90^\circ - E) \ Sin \gamma \ Cos(90^\circ + D)$$

This equation may be written as its equivalent:

$$\Sin E_c = \Sin E \ Cos \gamma - \Cos E \ Sin \gamma \ Sin D$$

which is Equation 1.

Again referring to spherical triangle pMN, from well-known spherical trigonomical formula:

$$\begin{aligned} \Sin \text{angle } pMN \ Cot \text{angle } MNp &= \Sin \gamma \ Cot pM - \Cos \gamma \ Cos \text{angle } pMN \\ \text{But} \quad pN &= 90^\circ - E_c, \ pM = 90^\circ - E, \ MN = \gamma \end{aligned}$$

and

$$\text{Angle } pMN = 90^\circ + D$$

Also

$$\text{Angle } MNp = 90^\circ - D_c$$

Therefore:

$$\begin{aligned} \Sin(90^\circ + D) \ Cot(90^\circ - D_c) &= \Sin \gamma \ Cot(90^\circ - E) - \Cos \gamma \ Cos(90^\circ + D) \\ &= \Sin \gamma \ Cot(90^\circ - E) - \Cos \gamma \ Cos(90^\circ + D) \end{aligned}$$

which may be written as its equivalent:

$$\Cos D \ Tan D_c = \Sin \gamma \ Tan E + \Cos \gamma \ Sin D$$

which may be written as its equivalent:

$$\Tan D_c = \frac{\Sin E \ Sin \gamma + \Cos E \ Cos \gamma \ Sin D}{\Cos E \ Cos D}$$

Multiply numerator and denominator by $\Cos E$, then

$$\Tan D_c = \frac{\Sin E \ Sin \gamma + \Cos E \ Cos \gamma \ Sin D}{\Cos E \ Cos D}$$

which is the aforesaid Equation 2.

The mechanism arranged in accordance with this invention does not solve these precise equations, but solves the problem by means of the approximate equations as follows:

$$(3) \ E_c = E - K_1 f(E) (1 - \Cos K_2 \gamma) - K_3 D \ Sin K_4 \gamma$$

$$(4) \ D_c = f(E) \ Sin K_2 \gamma + D \ Cos K_4 \gamma$$

In these formulae K_1 , K_2 , K_3 and K_4 are constants, and $f(E)$ is a function of the coordinate E, as will be explained in greater detail hereinafter.

Equations 3 and 4 are empirical equations, and approximately solve the problem illustrated in

Fig. 2. In a specific problem where the range or elevation E may vary from the limit 0° to 40° , where the deflection D may vary between -6° and $+6^\circ$, and where the angle of cross roll γ may be between -20° and $+20^\circ$, the maximum errors that have been encountered with these equations are 7 minutes in elevation, and 33 minutes in deflection.

In this specific problem, the empirically determined values of K_1 , K_2 , K_3 and K_4 are

$$30 \quad \begin{array}{r} 31 \quad 29 \\ 43 \quad 21 \end{array}$$

1 and 1 respectively. Should the ranges of the problem be varied as to elevation, deflection and cross roll, or as to one or more of these factors, these values should be varied accordingly to control the error within reasonable limits. The value $f(E)$, empirically determined, is roughly a linear function of E, and expressed by the following equation:

$$(5) \ f(E) = \frac{1}{19} \left(18E - \frac{92}{17} \tan^{-1} \frac{\Sin 3.6E}{3.75 + \Cos 3.6E} \right)$$

Here again, this value may be and preferably should be varied if the limits of the problem vary, so as to correct the maximum errors.

Referring more specifically to Fig. 1, it will be understood that the calculated or ascertained values of elevation E and of deflection D are introduced into the mechanism by means of shafts 10 and 11, and that the angle of cross roll is introduced into the mechanism by the shaft 12. It will be understood that these values E, D and γ will be generated by any suitable auxiliary mechanisms which form no part of this invention.

The value $f(E)$ is generated in the mechanism 13. The mechanism 13 comprises a cam 14 having a spiral-like, cam groove 15 in which a follower pin 16 operates. The follower pin 16 controls the movement of a slide rack 17 with which a gear 18 cooperates. The cam 14, as shown, is provided on its periphery with a gear 19 which is driven by a spur gear 20. This gear in turn is driven by a shaft 21 that is driven by the shaft 10 through bevel gears 22. The cam groove 15 is so arranged that it operates the rack 17 to generate in the movement of the gear 18 the value $f(E)$ as expressed by Equation No. 5. The gear 18 drives a shaft 23 which is connected to the input of a differential 24 by a gear 24a, the other input of which is directly connected with the shaft 10 introducing the value of E as calculated. The constant K_1 is introduced into the mechanism by properly proportioning the number of teeth on the gear 24a to the number of teeth on the dif-

ferential input gear driven thereby, and this constant is multiplied by $f(E)$ in the differential. Also in the differential 24, the value $K_{1f}(E)$ is subtracted from E so that the output shaft 25 of the differential generates the value $E - K_{1f}(E)$.

A resolving mechanism 26 generates the values $f(E) \cos K_{2\gamma}$ and $f(E) \sin K_{2\gamma}$. This mechanism comprises a pin 27 which is mounted for radial movement on a screw 28. The screw 28 is turned to adjust the position of the pin 27 by a member 29 which drives a bevel gear 30 secured to the member and which gear meshes with a bevel gear 31 attached to the screw. The member 29 is rotated by means of a spur gear 31a which meshes with gear teeth 29a on the periphery of the member, as shown. The gear 31a is driven by a shaft 32 which introduces $f(E)$. The shaft 32, as shown, is driven from a shaft 33 through bevel gears 34, and the shaft 33 in turn is driven from the shaft 23 by means of bevel gears 35 and a differential 36, the function of which will be described in greater detail hereinafter.

The screw 28 is mounted on a gear member 37 by means of a block 37a attached to the member 37, and, as shown, projects through the gear members 29 and 30. The gear member 37 is mounted for free relative rotation with reference to the member 29, and on the same axis as the member 29. The member 37 has gear teeth 38 on its periphery. This member 37 is driven by a gear 39 mounted on a shaft 40 which is connected through bevel gears 41 with a shaft 42 which in turn is connected with the cross level shaft 12 through bevel gears 43. The gear 39 introduces the factor K_2 . The factor $K_{2\gamma}$, therefore, is introduced by the shaft 40 which rotates the gear 37 in accordance with this value, and therefore, superimposes upon the radial movement of the pin 27 an angular movement which is proportional to the value $K_{2\gamma}$.

The resultant movement of the pin 27 is imparted to slides 44 and 45 fixed at right angles to each other, and intersecting each other at the pin 27. The slide 44 is arranged to move only in a horizontal direction and the slide 45 is arranged to move only in a vertical direction.

The movement of the pin radially in accordance with the value $f(E)$ and angularly in accordance with the value $K_{2\gamma}$ imparts to the slides 44 and 45 respectively such motions that they generate the values $f(E) \sin K_{2\gamma}$ and $f(E) \cos K_{2\gamma}$, respectively. The horizontal motion of the slide 44 drives a shaft 46. For this purpose, the slide 44 is provided with a gear rack 47 which meshes with a gear 48 mounted on the shaft 46. The vertical motion of the rack 45 is imparted to a shaft 49 by means of a rack 50 on the slide and a gear 51 on the shaft. The motions of the shafts 49 and 46 are utilized to generate the corrected adjustments E_c and D_c , as will be described in greater detail hereinafter.

The purpose of the differential 36 will now be understood. It will be observed that when the shaft 42 is operated to rotate the member 37 and the screw 28 as a unit, the shaft 32 for the moment may be considered fixed; therefore, when the member 37 is rotated to introduce $K_{2\gamma}$, motion would be imparted to the screw 28 to move the pin 27 radially by the interaction of the gearing 30 and 31. The differential 36 introduces the rotation of the shaft 42 into the calculating device 26 to unwind, so to speak, the rotation imparted to the screw 28 due to this interaction of the gears 30 and 31 so that the position of the pin 27 ra-

dially on the screw 28 is not affected by the rotation of the member 37.

The motion of the shaft 11 which introduces the calculated value of deflection D and the shaft 42 which measures the ascertained value of the angle of cross roll γ also operate a resolving mechanism 53 which is similar to the mechanism 26. Here the pin 54 mounted on the screw 55 is operated radially by means of a gear plate 56 which in turn is operated by means of the shaft 11 operating through a differential device 57, a shaft 58 and a gear 59 meshing with gear plate 56. The gear 56, as shown, operates the screw 55 through bevel gears 60. The pin 54 is operated angularly in accordance with the angle of cross roll γ by means of a gear 61 which supports the screw and is driven by a gear 62 that in turn is driven by a shaft 63. The gear 62 is arranged to introduce the factor K_4 .

The motion of the pin 54 is imparted to slides 65 and 66 arranged at right angles to each other and intersecting each other at the pin, as shown. The slide 65 can have only vertical motion and the slide 66 can have only horizontal motion. The mechanism 53 is such that the motion imparted to the slide 65 is the value $D \sin K_4\gamma$, and the movement of the slide 66 generates $D \cos K_4\gamma$. The motion of the slide 65 is imparted to a shaft 67 through a gear rack 68 mounted on the slide and meshing with a gear 69 on the shaft 67. The shaft 67 drives a shaft 70 through the bevel gears 71. The motion of the slide 66 is imparted to a rack 71 mounted on it and this motion of the rack is imparted to a shaft 72 by means of a gear 73 mounted on the shaft and meshing with the rack.

The differential device 57 functions as does the differential 36, that is, to compensate for the radial movement that would be imparted to the pin 54 by the interaction of the gears 60 when gear 61 is adjusted.

The motions of these two shafts 70 and 72 are also utilized to generate the values E_c and D_c . That of the former is combined with the motion of the shaft 25 to produce the value E_c . The shaft 25, as pointed out previously, generates the value $E - K_{1f}(E)$, and this value is introduced by the shaft 25 into a differential device 74; also feeding into this differential device 74 is the shaft 75 which is driven from the shaft 49 by bevel gears 76 to generate the value $f(E) \cos K_{2\gamma}$. As shown, the shaft 75 is connected to an input gear of the differential 74 by means of a gear 75a. Here the constant K_1 is introduced into the mechanism by properly proportioning the number of teeth on the gear 75a to the number of teeth on the differential input gear driven thereby, and this constant is multiplied by $f(E)$ in the differential. The value $K_{1f}(E) \cos K_{2\gamma}$ is added to the input of the shaft 25 in the differential 74 to generate the value $E - K_{1f}(E) + K_{1f}(E) \cos K_{2\gamma}$ so that this resultant is generated by the output shaft 77 of the differential 74. The value $D \sin K_4\gamma$ generated in the shaft 70 is subtracted from this value generated in the shaft 77 in a differential 78 to generate in the output shaft 79 of the differential the following value:

$$E - K_{1f}(E) + K_{1f}(E) \cos K_{2\gamma} - K_3 D \sin K_4\gamma$$

the factor K_3 being introduced in the differential 78. The above value is the same as the value expressed in Equation 3:

$$E - K_{1f}(E) (1 - \cos K_{2\gamma}) - K_3 D \sin K_4\gamma$$

which is E_c

75 The output of shaft 72, which is $D \cos K_4\gamma$,

is added in the differential 80 to the output of shaft 46, which is $f(E) \sin K_2\gamma$, to generate in the output shaft 81 of the differential the summation $f(E) \sin K_2\gamma + D \cos K_4\gamma$, which, as pointed out above, is the value of corrected deflection D_c as expressed in Equation 4.

In the operation of the apparatus, it will be understood that the values of E and D will be fed into the apparatus by means of the shafts 10 and 11 as they are calculated, and that the angle of cross roll γ will be continuously introduced into the mechanism by means of the shaft 12. The apparatus continuously regenerates these values in the manner previously described to generate the corrected adjustments to be applied to the gun, E_c and D_c , the shafts 79 and 81 generating these values, respectively. The values generated in these shafts may be used in any suitable manner to direct the gun, such as to operate suitable gun indicating mechanism (not shown).

It will be understood that the apparatus of this invention may also be used in other applications where it is desired to maintain the position of a point in space fixed on the surface of a sphere even though the original axes of the point are inclined.

While we have shown a particular embodiment of our invention, it will be understood, of course, that we do not wish to be limited thereto since many modifications may be made, and we, therefore, contemplate by the appended claims to cover any such modifications as fall within the true spirit and scope of our invention.

What we claim as new and desire to secure by Letters Patent of the United States is:

1. In a trunnion tilt corrector mechanism for a gun mounted on a swaying foundation, mechanism for generating a corrected adjustment to be applied to said gun in deflection comprising, a first input shaft and a second input shaft for introducing ascertained values to be applied in elevation and deflection respectively, a third input shaft for introducing the angle of cross roll of the mount around the line of sight of a target, means operated responsively to said first input shaft for generating a predetermined function of elevation, a resolving mechanism operated responsively to said last-named means and said third input shaft for generating a product of said function of elevation and a predetermined trigonometric function of said angle of cross roll, a second resolver operated responsively to said second and third input shafts for generating a predetermined product of said ascertained deflection and a predetermined trigonometric function of the angle of cross roll, and a fourth shaft operated by said first and second resolvers so that its movement generates said corrected deflection adjustment as the sum of the products of said function of elevation and predetermined trigonometric function of the angle of cross roll and of the ascertained value of deflection and predetermined trigonometric function of the angle of cross roll.

2. In a trunnion tilt corrector mechanism for a gun mounted on a swaying foundation, mechanism for generating a corrected adjustment to be applied to said gun in elevation comprising a first input shaft and a second input shaft for introducing ascertained values to be applied in elevation and deflection respectively, a third input shaft for introducing the angle of cross roll of the mount around the line of sight of a target, means operated responsively to said first input shaft for generating a predetermined function of elevation,

a resolving mechanism operated responsively to said last-named means and said third input shaft for generating a product of said function of elevation and a predetermined trigonometric function of said angle of cross roll, a fourth shaft operated responsively to said first input shaft and said means for generating said predetermined function of elevation so that the movement of said fourth shaft generates the difference between said ascertained value of elevation and said function of elevation, a second resolver operated responsively to said second and third input shafts for generating a predetermined product of said ascertained deflection and a predetermined trigonometric function of the angle of cross roll, a fifth shaft operated responsively to said first resolver and said fourth shaft so that its movement generates the summation of the difference of ascertained elevation and said function of elevation and the product of said function of elevation and predetermined trigonometric function of said angle of cross roll generated in said first resolver, and a sixth shaft operated responsively to said second resolver and said fifth shaft so that its movement generates the difference between the value generated in said fifth shaft and the product of ascertained deflection and predetermined trigonometric function of the angle of cross roll generated in said second resolver.

3. In a trunnion tilt corrector mechanism for a gun mounted on a swaying foundation, mechanism for generating corrected elevation adjustments to be applied to said gun comprising three input shafts, the first to introduce the ascertained value of the elevation adjustment to be applied to said gun, the second to introduce the ascertained value of the deflection adjustment to be applied to said gun, and the third to introduce the angle of cross roll of the mount around the line of sight of a target, a resolver operated responsively to said second and third shafts for deriving the product of ascertained deflection and a predetermined function of the angle of cross roll, first means operated by said first shaft for deriving a predetermined function of ascertained value of elevation, second means operated by said first means and said first shaft for generating the difference between ascertained elevation and said predetermined function of ascertained value of elevation, a second resolver operated by said first means and said third shaft for deriving the product of said function of ascertained value of elevation and a predetermined function of the angle of cross roll, third means operated by said second resolver and said second means for adding the values generated thereby, and fourth means operated by said first resolver and said third means for subtracting said product generated in said first resolver from the value derived in said third means to generate the corrected elevation adjustment.

4. In a trunnion tilt corrector mechanism for a gun mounted on a swaying foundation, mechanism for generating a corrected adjustment to be applied to said gun in elevation comprising, a first input shaft and a second input shaft for introducing ascertained values to be applied in elevation and deflection respectively, a third input shaft for introducing the angle of cross roll of the mount around the line of sight of a target, means operated responsively to said first input shaft for generating a predetermined function of elevation, a resolving mechanism operated responsively to said last-named means and said third input shaft

for generating a product of said function of elevation and a predetermined function of said angle of cross roll, a fourth shaft, means operating said fourth shaft responsively to said first input shaft and said means for generating said function of elevation so that the movement of said fourth shaft generates the difference between said ascertained value of elevation and said function of elevation, a second resolving mechanism operated responsively to said second and third input shafts for generating a predetermined product of said ascertained deflection and a predetermined function of the angle of cross roll, a fifth shaft, means operating said fifth shaft responsively to said first resolving mechanism and said fourth shaft so that the movement of said fifth shaft generates the summation of the difference of ascertained elevation and said function of elevation and the product of said function of elevation and predetermined function of said angle of cross roll generated in said first resolving mechanism, a sixth shaft, and means operating said sixth shaft responsively to said second resolving mechanism and said fifth shaft so that the movement of said sixth shaft generates the difference between the value generated in said fifth shaft and the product of ascertained deflection and predetermined function of the angle of cross roll generated in said second resolving mechanism.

5. In a trunnion tilt corrector mechanism for a gun mounted on a ship, mechanism for generating a corrected adjustment to be applied to said gun in elevation E_c comprising first, second and third shafts for introducing respectively ascertained values of elevation E , deflection D , and the angle of cross roll γ of said ship about the line of sight of a target, a cam operated by said first shaft and a follower operated by said cam, said cam and follower constructed and arranged so that the movement of said follower generates a predetermined function of the ascertained elevation value $f(E)$, first generating means operated responsively both to said movement of said follower and to the operation of said third shaft in introducing the ascertained angle of cross roll γ constructed and arranged to generate the product $f(E) \cos K_2\gamma$, second generating means operated responsively both to said second and third shafts in introducing respectively the ascertained values of deflection D and angle of cross roll γ constructed and arranged to generate the product $D \sin K_4\gamma$, a fourth shaft, means operating said fourth shaft responsively both to the operation of said first shaft and said follower so that the movement of said fourth shaft generates the difference $E - f(E)$, means operated by said fourth shaft and said first generating means for generating the summation: $[E - f(E)] + [f(E) \cos K_2\gamma]$, and means operated by said last-named means and also operated by said second generating means for generating the difference:

$$[E - f(E)] + [f(E) \cos K_2\gamma] - D \sin K_4\gamma$$

6. In a trunnion tilt corrector mechanism for a gun mounted on a ship, first, second and third shafts for introducing respectively ascertained values of elevation E , and deflection D , and the angle of cross roll γ of said ship about the line of sight of a target, a cam operated by said first shaft and a follower operated by the cam so that its movement generates a predetermined function of the calculated elevation value $f(E)$, first generating means operated responsively to said follower and said third shaft for generating the

product $f(E) \sin \gamma$, second generating means operated responsively to said second and third shafts for generating the product $D \cos \gamma$, and means operated by said first and second generating means for generating the summation: $f(E) \sin \gamma + D \cos \gamma$.

7. In a trunnion tilt corrector mechanism for a gun mounted on a ship, mechanism for generating corrected adjustments to be applied to said gun in elevation E and deflection D comprising first, second and third shafts for introducing respectively ascertained values of elevation E , the deflection D and the angle of cross roll γ of said ship about the line of sight of a target, first means operated responsively to the operation of said first shaft for generating a predetermined function of the ascertained elevation value of $f(E)$, means operated responsively to the operation of said first means and said third shaft for generating products of $f(E)$ and predetermined functions of γ and further means operated responsively to said second and third shafts for generating products of D and predetermined functions of γ , means operably connected to said first shaft, said first means, and to said means for generating said products so as to be operated thereby to generate corrected values of elevation in terms both of said products of $f(E)$ and D and said predetermined functions of γ , and also in terms of said ascertained values of $f(E)$ and of E , and means operably connected to said means for generating said products so as to be operated thereby to generate corrected values of deflection in terms both of said products $f(E)$ and D and said predetermined functions of γ .
8. In gun directing mechanism for a gun mounted on a ship, mechanism for generating corrected adjustments to be applied to said gun in elevation E_c and deflection D_c comprising first and second shafts for introducing ascertained values of elevation E and deflection D measured with reference to the true vertical and horizontal, a third shaft for introducing the angle of cross roll γ of said ship about the line of sight of a target, a calculating mechanism having a pin mounted for circular movement about a fixed axis and for radial movement with reference to said axis, a pair of mutually perpendicular slides mounted for movement at right angles to each other and intersecting each other at said pin where the pin is connected to them for operating them, a second calculating mechanism similar to the first, a cam operated by said first shaft and a follower operated by the cam to generate a predetermined function of the elevation value $f(E)$, means connecting the pin of the first mechanism with said follower so that the pin is moved radially in accordance with the movement of said follower, means connecting said second shaft with said second pin so that it is moved radially in accordance with the calculated value D , means connecting both of said pins with said third shaft so that they are rotated about their axes in accordance with the angle of cross roll γ of the ship about the line of sight to a target, the slides of the first calculating mechanism thereby measuring the products $f(E) \sin K_2\gamma$ and $f(E) \cos K_2\gamma$ and those of the second the products $D \sin K_4\gamma$ and $D \cos K_4\gamma$, and means operated by said first shaft in introducing said ascertained values of elevation E , said cam follower in generating said value $f(E)$ and also by the slides of said calculating mechanisms in generating the products $f(E) \cos \gamma$ and $D \sin \gamma$ for generating the corrected value of elevation E_c to be applied to said gun, and means operated re-

sponsively to said slides of said calculating mechanisms in generating the products $f(E) \sin \gamma$ and $D \cos \gamma$ for generating the corrected value of deflection D_c to be applied to said gun.

9. In a trunnion tilt corrector mechanism for a gun mounted on a ship, mechanism for generating corrected adjustments to be applied to said gun in elevation E_c and deflection D_c comprising first, second and third shafts for introducing respectively ascertained values of elevation E , and deflection D , and the angle of cross roll γ of said ship about the line of sight to a target, a cam operated by said first shaft and a follower operated by the cam to generate a determined function of the calculated elevation value $f(E)$ having approximately the following value:

$$\frac{1}{19} \left(18E - \frac{92}{17} \tan^{-1} \frac{\sin 3.6E}{3.75 + \cos 3.6E} \right)$$

first generating means operated responsively to said follower and said third shaft for generating the products

$$f(E) \cos \frac{29}{21} \gamma$$

and

$$f(E) \sin \frac{29}{21} \gamma$$

second generating means operated responsively to said second and third shafts for generating the products $D \sin \gamma$ and $D \cos \gamma$, and means operated responsively to said first shaft, said cam follower in generating said value $f(E)$ and said first and second generating means constructed and arranged to utilize said ascertained values of elevation E introduced by said first shaft, said value $f(E)$ generated by said cam follower, and said products

$$f(E) \cos \frac{29}{21} \gamma$$

and $D \sin \gamma$ generated by said first and second

- generating means to generate the corrected adjustment in elevation E_c to be applied to said gun, and means operated responsively to said first and second generating means constructed and arranged to utilize said products $f(E) \sin \gamma$ and $D \cos \gamma$ generated by said first and second generating means to generate the corrected adjustment in deflection D_c to be applied to said gun.
10. In a trunnion tilt corrector mechanism for a gun mounted on a swaying foundation, mechanism for generating a corrected adjustment to be applied to said gun in deflection comprising, a first input shaft and a second input shaft for introducing ascertained values to be applied in elevation and deflection respectively, a third input shaft for introducing the angle of cross roll of the mount around the line of sight of a target, means operated responsively to said first input shaft for generating a predetermined function of elevation, a resolving mechanism operated responsively to said last-named means and said third input shaft for generating a product of said function of elevation and a predetermined function of said angle of cross roll, a second resolving mechanism operated responsively to said second and third input shafts for generating a predetermined product of said ascertained deflection and a predetermined function of the angle of cross roll, a fourth shaft, and connection means between said fourth shaft and said first and second resolvers so that said fourth shaft is moved to generate said corrected deflection adjustment as the sum of the products of said function of elevation and predetermined function of the angle of cross roll generated in said first resolving mechanism and of the ascertained value of deflection and predetermined function of the angle of cross roll generated in said second resolving mechanism.
